UNITED STATES PATENT OFFICE.

MATH N. SCHNEIDER, OF NORTH MILWAUKEE, WISCONSIN.

REGISTER.

1,230,381.

Specification of Letters Patent. Patented June 19, 1917.

Application filed October 12, 1916. Serial No. 125,227.

To all whom it may concern:

Be it known that I, MATH N. SCHNEIDER, a citizen of the United States, residing at North Milwaukee, in the county of Milwaukee and State of Wisconsin, have invented 5 certain new and useful Improvements in Registers, of which the following is a specification.

This invention relates to registers, and 10 more particularly to a pocket register to be used for registering the numbers of automobiles and similar vehicles.

One of the main objects of the invention is to provide a register of the character 15 stated of simple construction and operation which can be easily carried in the pocket and is adapted to be locked against operation when desired. A further object is to provide a register having means for 20 feeding a strip of paper about a roll and for perforating this strip to indicate the desired number. A still further object is to provide a register having distinguishing marks for indicating from which State or 25 Territory the vehicle comes and whether or not it is exceeding the speed limit. Further objects will appear from the detail description.

In the drawings:

30 Figure 1 is a top plan view of the register;

Fig. 2 is a vertical central sectional view taken substantially on line 2—2 of Fig. 1;

Fig. 3 is a partial section taken on line 35 6—6 of Fig. 1;

Fig. 4 is a transverse section taken near the top of the register looking down;

Fig. 5 is a transverse section taken near the center of the register;

40 Fig. 6 is a section on line 6—6 of Fig. 1;

Fig. 7 is a side view of the paper roll and the upper feed roll;

Fig. 8 is a detail top plan view of the 45 print rods enlarged to show the assembly of the same;

Fig. 9 is a detail of the mounting of one of the print rods;

Fig. 10 is a detail of the connection between one of the operating rods and a print 50 rod.

The body or casing 1 of the register is of barrel shape, and is closed at its upper end. At its lower end the body is threaded exteriorly to receive an interiorly threaded 55 closure member 2. At the center of body 1 two supporting plates 3 are secured in

parallelism and in spaced relation. Each of these plates is turned outward at right angles at each end to provide a securing flange 4 which is secured to the inner face 60 of casing 1.

The plates 3 are of approximate triangular shape having their apexes directed downwardly. These plates are provided with alined apertures at their apexes which 65 rotatably receive the supporting rod 5 of a spool 6. This spool is adapted to contain a roll of parchment paper. The strip of paper 7 contained by this spool is passed upward over the upper feed roll 8 rotatably supported between the plates 3 near the top thereof, and is then passed downward between roll 8 and the lower feed roll 9 which is rotatably supported between the plates 3 parallel with roll 8. The rolls 8 70 and 9 are made of rubber, cork, or other suitable resilient material, and are so spaced as to grip securely the downwardly extending portion 7a of the paper strip 7.

The casing 1 is provided, above its vertical center, with a plurality of radially disposed equally spaced U-brackets 10. These brackets are secured to the inner face of the casing and project inwardly from the same. A print rod or bar 11 is pivotally 80 mounted at its lower end in each bracket 10 as at 12. This bar is provided with an angularly disposed shank 11a and body 11b. These members all incline upwardly and inwardly toward the center of the casing 1 and 85 are so disposed that their upper ends are positioned in circular arrangement, and are closely adjacent. A locking screw 13 is threaded through the top 14 of casing 1. This screw is adapted, when in lowered position, to pass between the inner ends of the print bars 11 and acts to positively prevent downward movement of these bars. A wire spring 15 is mounted about the pivot of each print bar. One arm of this spring is 90 in engagement with the under face of the shank portion 11a of the bar and the other arm engages the inner face of casing 1, the spring acting to normally hold the print bar in raised position.

105 Each print bar is provided, on its under face and near its inner end, with a numeral outlined in sharp pins or points, as at 16 in Fig. 8 of the drawings. These numerals extend from zero to 9, there being ten print 110 bars in all. The print bars are of such length that, when depressed, the numeral

carried thereby will engage the upper surface of roll 8 at the center thereof. In this manner the points carried by the bar will act to perforate the paper strip 7 thus marking thereon the numeral of the bar which is depressed. For the purpose of depressing the bars each bar is provided with an operating rod 17 which is pivotally secured at its lower end to the body portion 11^b of the print bar 11, as at 18 in Fig. 10 of the drawings. Operating rod 17 is slidably mounted through an aperture through the upper end of casing 1 and extends above the casing being provided, on its upper end, 15 with a key or head 19 upon which is marked the numeral of the particular bar to which the head 17 is connected. This will be clear from Fig. 1 of the drawings. The numerals of the bars are so disposed thereon that 20 no matter which bar is depressed the numeral of that particular bar will be marked upon the paper strip 7 transversely of the strip. By this arrangement, by depressing the proper keys 19, any desired number may 25 be marked on the strip.

A circular guide head 20 is slidably mounted within the casing 1 and above the rolls 8 and 9. This head is provided with a plurality of radially disposed notches 21, 30 and is arranged concentric with casing 1. These notches are so disposed as to receive the body portions 11^b of the print bars 11. This provides guiding means thus insuring proper and accurate operation of the print 35 bars when depressed. The head 20 is provided with two diametrically opposite depending arms 22. Each of these arms is provided with an upper vertical slot 23 and a lower slot 24. The shaft 5 of spool 6 is 40 extended so as to project laterally through each plate 3 and extends through the lower slot 24 of arm 22. A short sleeve 25 is rotatably mounted on shaft 5 near each end thereof so as to provide bearings which operate in the lower slots of the arms 22. The shaft 26 of feed roll 8 is similarly extended and is provided, at each end, with bearing sleeves 29 operative in the upper slots 23 of arms 22. Suitable securing nuts are secured 45 on the ends of the shafts 5 and 26 so as to prevent lateral movement of the arms 22, and consequently head 20, transversely of the casing 1. This provides a sliding mounting for the head so as to permit vertical movement of the same. A leaf spring 30 is secured to each plate 3. The inner portion of this spring extends beneath an outwardly projecting pin 31 carried by arm 22. These two springs act to normally hold 50 the head 20 in raised position. The notches 21 of the head are of such depth that, when a print bar 11 is depressed so as to perforate the paper strip 7, this bar will engage the head and force the same downward a predetermined distance.

The shaft 32 of roll 9 is extended at each end so as to project through the supporting plate 3. A ratchet wheel 33 is secured on this shaft adjacent each plate 3. This shaft 32 is extended so as to project through one 70 side of casing 1, a gripping wheel or disk 32^a being secured on the outer end of the shaft. This provides means for rotating roll 9 manually so as to feed the paper strip between the rolls 8 and 9, when desired. A 75 pawl 34 is pivotally mounted at its lower end on the inner face of arm 22. The upper end of this pawl is normally held in operative engagement with the wheel 33 by a leaf spring 35 secured to the arm 22 above pawl and normally acting to force the pawl downward. When the head 20 is depressed in the manner previously described the pawls 34 actuate ratchets 33 so as to cause 80 rotation of roll 9. The roll 9 co-operates 85 with the roll 8 to grip frictionally the paper strip 7, as previously described, so that when the roll 9 is rotated the strip is moved downwardly about roll 8 and is simultaneously unwound from spool 6 for a predetermined 90 distance. When the key is released the leaf springs 30 act to return guide head 20 to its initial position.

It will be understood, of course, that when the points of one of the printing heads 95 engage the paper strip, the strip is secured against movement. To prevent tearing of the strip the roller 9 is so mounted, relative to roller 8, as to permit slippage of the same during the actual perforating of the 100 strip. In this manner roller 9, in addition to feeding the paper strip the required distance when a key is depressed, also acts to maintain the paper stretched snugly over roller 8 during the perforating operation, 105 thus eliminating all possibility of slack in the strip and insuring accuracy of operation. As will be noted more clearly from Figs. 2 and 3 of the drawings, the printing and perforating heads are normally spaced 110 a considerable distance above roller 9, so that, when one of the heads is depressed, the strip will be fed forward by roller 9 a distance slightly greater than the height of the numerals of the heads, thus presenting 115 an unperforated portion of the paper strip for engagement by the points of the head being depressed. By this means, I insure accuracy of operation and eliminate the necessity of supplemental feeding means for 120 feeding the paper strip between the rolls, this being accomplished automatically when a perforating head is depressed.

Two arcuate printing heads 36 and 36^a are pivotally mounted on the supporting 125 plates 3 near the upper edge thereof and closely adjacent the sides of roll 8, each plate having an integral ear 36^b to support the shaft for head 36^a. Each of these heads is provided, on its under face, with an ab- 130

5 abbreviation of some State or Territory outlined in the points 37. An operating rod 38 is pivotally connected at its lower end to each printing head. This rod extends 10 through an aperture 39 through the top 14 of casing 1, and is provided on its upper end with a head or key 40 which is marked similarly to the abbreviation or figure outlined on the printing head to which the rod is connected. A coil spring 41 is confined between the key 40 and the top of the casing and acts to normally hold the rod 38 and consequently the head 36, in raised position. The aperture 39 is somewhat larger than the 15 rod 38 so as to permit slight lateral play of the same thus insuring proper operation of the rod. There are four of these printing heads 36 and 36^a in all, two at each end of the roll 8 rockably mounted on transverse 20 supporting rods or shafts 36^c secured between the plates 3. Each printing head is provided with some suitable abbreviation, such as "Wis." for Wisconsin, "Min." for Minnesota and "Ill." for Illinois. One of 25 the heads may be provided with the abbreviation "Sp." for speed. This will be clear from Fig. 1 of the drawings. By perforating the paper strip 7 so as to indicate the number of an automobile or similar vehicle, and then depressing the proper head 36 to indicate the State from which the automobile came and, if the automobile is exceeding the speed limit, depressing the head marked "Sp.", a complete record is im- 30 printed upon the paper strip giving the number of the automobile, the State from which it came, and the fact that it was exceeding the speed limit. This provides a permanent record whereby the owner of the 35 automobile may be identified. Of course other abbreviations may be used in the place of those illustrated. The perforations made by the printing heads 36 will be to one side of the strip 7, closely adjacent the figures 40 printed at the center of the strip, but not close enough to such figures as to in any way interfere with the reading of the number.

45 After a number has been printed on the strip 7 in the manner stated, the closure member 2 may be removed from the casing 1 and the portion of the strip bearing this number torn off, if desired. For this purpose a part of the lower edge of the casing 1 is beveled inwardly to provide a cutting 50 edge, as at 1^a. By drawing the portion 7^a of strip 7 outward into engagement with this cutting edge the desired portion of the strip may be quickly and easily severed. Where there are several numbers imprinted 55 in succession on the strip the abbreviations imprinted at the side of the strip by the heads 36 serve to divide or separate these numbers thus preventing confusion of the same.

60 65 When it is not desired to use the register

the locking screw 13 may be turned in so as to pass between the inner ends of the print bars 11 thus preventing movement of the same. By moving this screw outward the bars are released so that the register 70 may be operated in the manner described.

75 There may be slight changes made in the construction and arrangement of the different parts of my invention without departing from the field and scope of the same, and I intend to include all such variations, as fall within the scope of the appended claims, in this application in which a preferred form only of my invention is disclosed.

80 What I claim is:

1. In registers, the combination of a casing, a plurality of radially disposed upwardly inclined print bars pivotally mounted within the casing, the bars being so relatively disposed that, when in normal position, their upper ends are closely adjacent and disposed in circular arrangement, a locking screw threaded through the top of the casing and adapted to engage between 90 the inner ends of the print bars, a roll rotatably mounted within the casing beneath the inner ends of the print bars, a strip passed about the roll, means for depressing any one of the print bars optionally, and 95 means for simultaneously causing movement of the said strip when a print bar is depressed.

2. In registers, the combination of a casing, a pair of spaced parallel supporting plates secured in the casing, two closely adjacent rolls rotatably mounted between the plates, a plurality of radially disposed upwardly inclined print bars mounted on the inner face of the casing, means for depressing any one of said bars optionally, the inner one of said rolls being positioned beneath the inner ends of the print bars, a strip passed about the inner roll and between the two said rolls so as to be frictionally gripped thereby, and means for causing partial rotation of one of said rolls when a print bar is depressed.

3. In registers, the combination of a casing, two parallel supporting plates mounted in spaced relation within the casing and secured thereto, a pair of gripping rolls rotatably mounted between the plates closely adjacent each other, a spool rotatably mounted between the plates below the inner one of said rolls, a plurality of radially disposed print bars pivotally mounted within the casing and provided at their inner ends with marking elements arranged to engage the upper surface of the said inner roll when the print bars are depressed, means for optionally depressing any one of said print bars, and means for simultaneously causing partial rotation of one of said rolls when one of the print bars is depressed.

4. In registers, the combination of a casing, two parallel supporting plates mounted in spaced relation within the casing and secured thereto, a pair of closely adjacent rolls rotatably supported between the said plates, a plurality of radially disposed print bars pivotally mounted within the casing, the said bars being provided on their inner ends with marking elements and being so 5 relatively disposed that, when in normal position, their inner ends are closely adjacent and are arranged in a circle, means carried by the casing and adapted to engage between the inner ends of the bars for simultaneously 10 locking all of said bars against movement, a vertically movable guide head mounted above the said rolls adapted to be depressed when one of the print bars is depressed, and connections between one of said rolls and 15 the head whereby the roll is partially rotated through a predetermined distance when the head is depressed.
5. In registers, the combination of a casing, a pair of parallel supporting plates 20 mounted within the casing in spaced relation and secured thereto, a pair of friction rolls rotatably supported between the plates and disposed closely adjacent each other, a spool mounted beneath the inner one of said 25 rolls, a plurality of radially disposed print bars pivotally mounted within the casing and provided at their inner ends with marking elements, means for depressing said bars, a guide head slidably mounted on the shafts 30 of the said inner roll and spool so as to have vertical movement, said head being provided with a plurality of radially disposed notches adapted to receive the print bars when the same are depressed, a ratchet wheel 35 secured on the shaft of the outer one of said 40
- friction rolls, and a pawl engaging said ratchet wheel whereby predetermined rotation of said roll is caused when the guide head is depressed.
6. In registers, the combination of a casing, a pair of parallel supporting plates mounted within the casing in spaced relation and secured thereto, a pair of friction rolls rotatably supported between the plates and disposed closely adjacent each other, a spool 45 mounted beneath the inner one of said rolls, a plurality of radially disposed print bars pivotally mounted within the casing and provided at their inner ends with marking elements, means for depressing said bars, a 50 guide head slidably mounted on the shafts of the said inner roll and spool so as to have vertical movement, said head being provided with a plurality of radially disposed notches adapted to receive the print bars when the 55 same are depressed, a ratchet wheel secured on the shaft of the outer one of said friction rolls, a pawl engaging said ratchet wheel whereby predetermined rotation of said roll is caused when the guide head is depressed, a 60 plurality of printing heads pivotally mounted on the said supporting plates closely adjacent the inner one of the gripping rolls and provided with marking elements on their under faces, means for normally holding the said heads away from the said inner roll, and means for moving any one of said 65 heads optionally toward the said inner roll.

In testimony whereof I affix my signature in presence of two witnesses.

MATH N. SCHNEIDER.
